UNITED STATES PATENT OFFICE.

HENRY MARTIN BOEHM, OF MINNEAPOLIS, MINNESOTA.

DESIGN FOR A CARTON.

Application filed March 25, 1926. Serial No. 17,050. Term of patent 3½ years.

To all whom it may concern:

Be it known that I, HENRY M. BOEHM, a citizen of the United States, residing at Minneapolis, in the county of Hennepin and State of Minnesota, have invented a new, original, and ornamental Design for Cartons, of which the following is a specification, reference being had to the accompanying drawings, forming part thereof.

Figure 1 is a perspective view of the box looking toward one end and two of the sides, and

Figure 2 is a perspective view of the box looking from the other end and the other two sides.

The body portion of the box is black, but has been shown uncolored in order to prevent obscuring the drawings. The figures are lined conventionally to represent colors.

I claim:

The ornamental design for a carton, as shown and described.

HENRY MARTIN BOEHM.
